UNITED STATES PATENT OFFICE.

MICHEL JACOBS, OF NEW YORK, N. Y.

DESIGN FOR A DISPLAY-FIXTURE FOR SUSPENDERS OR THE LIKE.

SPECIFICATION forming part of Design No. 35,247, dated October 29, 1901.

Application filed August 30, 1901. Serial No. 73,881. Term of patent 7 years.

To all whom it may concern:

Be it known that I, MICHEL JACOBS, a citizen of the United States, and a resident of the city, county, and State of New York, have invented and produced a new, useful, and original Design for a Display-Fixture for Suspenders or the Like, of which the following is a specification, reference being had to the accompanying drawings, forming a part thereof.

In the said drawings, Figure 1 is a plan view of the display fixture, and Fig. 2 is a perspective view of the same.

A is the hoop or ring; B, the hub; C, the spokes, and D the hook-brackets, which project radially from the said hoop or ring.

Fig. 2 shows the contour or configuration of the hook-bracket D, which consists of a lower horizontally-disposed member *a*, which extends out radially from the hoop A, and an upper horizontally-disposed member *b*, which has at its outer end the curved loop-like portion *c*, which extends down below the

end of the lower member *a*, which it joins by a reverse curve at *d*.

The leading features of my design are the 25 loop-like portion *c* of the bracket, extending down below the member *a* and having a reverse-curved portion at *d*, which meets the member *a*, and also the fixture having a circular hoop, as seen in plan, with the hook-brackets projecting in a radial direction outwardly therefrom.

What I claim is—

The design for a display-fixture for suspenders and the like, substantially as shown 35 and described.

In witness whereof I have hereunto signed my name, this 28th day of August, 1901, in the presence of two subscribing witnesses.

MICHEL JACOBS.

Witnesses:

HENRY CONNETT,
PETER A. ROSS.
